UNITED STATES PATENT OFFICE.

MICHAEL F. DAVORAN, OF CINCINNATI, OHIO, ASSIGNOR TO THE CRANE & BREED MANUFACTURING COMPANY, OF CINCINNATI, OHIO, A CORPORATION OF OHIO.

APPARATUS FOR ELECTROPLATING.

1,318,054.

Specification of Letters Patent.

Patented Oct. 7, 1919.

Original application filed August 3, 1917, Serial No. 184,265. Divided and this application filed August 12, 1918. Serial No. 249,543.

To all whom it may concern:

Be it known that I, MICHAEL F. DAVORAN, a citizen of the United States, residing at Cincinnati, in the county of Hamilton and 5 State of Ohio, have invented certain new and useful Improvements in Apparatus for Electroplating, of which the following is a specification.

My invention relates to means for insuring good electric contact between a traveling article-carrier and the terminals of an electro-plating bath, and is especially useful in apparatus for electro-plating employing the continuous operation principle, such for instance as shown and described in my application for Letters Patent of the United States, for improvements in method of and apparatus for electro-plating, Serial No. 184,265, filed August 3, 1917, of which this 20 application is a division.

It is the object of my invention to provide cathode-bars for an electro-plating bath arranged in such manner as to receive a portion of an article-carrier therebetween 25 for making good electric contact with the bars; further, to provide a plating tank with cathode-bars and a traveling article-carrier so correlated that a contact-part of the article-carrier is received between the cathode-bars and urged into frictional lateral contact with the bars at the respective sides of said contact-part; further, to provide a plating tank with cathode-bars at different elevations and a traveling article-carrier having 30 a contact-part received between said cathode-bars and urged into lateral contact with said cathode-bars by gravity; and, further, to provide means arranged to lower the articles into the bath and pass the same 35 along the cathode-bars, with a contact-part of the article-carrier making lateral contact with the cathode-bars, and for lifting the article-carrier out of the bath after passing along the cathode-bars.

40 The invention will be further readily understood from the following description and claims, and from the drawings, in which latter:

Figure 1 is a side elevation of my improved device, partly broken away, and showing an article-carrier lowered into the plating tank at one end of the tank and having a contact-part thereof received between the cathode-bars, and showing an article-

carrier elevated out of the tank at the other 55 end of the tank.

Fig. 2 is a vertical cross-section of the same, taken on the line 2—2 of Fig. 1.

Fig. 3 is a plan view of the plating tank.

Fig. 4 is a detail in vertical cross-section 60 taken on the line 4—4 of Fig. 3, showing the means for attaching the anode-bars.

Fig. 5 is a detail in vertical section taken on the line 5—5 of Fig. 3, showing the means for attaching the cathode-bars.

Fig. 6 is a cross-section, taken on the line 6—6 of Fig. 2, showing a detail of the means for supporting the article-support.

Fig. 7 is a cross-section taken on the line 7—7 of Fig. 2, showing a detail of the article-carrier.

Fig. 8 is a detail in vertical section, taken on the line 8—8 of Fig. 1.

Fig. 9 is an axial section of the article-support, taken on the line 9—9 of Fig. 10; 75 and,

Fig. 10 is a cross-section of the same, taken in the plane of the line 10—10 of Fig. 9.

A suitable plating tank is represented at 11 and is exemplified as containing a suitable electrolytic plating bath 12. The plating bath comprises anode-bars 15, 16, which are electro-conductive bars having flexible electric conductors 17 electrically connected therewith, the flexible electric conductors 80 leading from a suitable battery or generator.

Anodes 18 are suspended in the electrolytic bath in the plating tank and are electrically connected with the anode-bars by an electro-conductive suspension-hook 19. Both of the 85 electrically connected anode-bars are positive pole bars of the plating bath and connect in multiple with one pole of the battery or generator.

The anode bars are suitably secured to the frame of the plating tank, as by means 90 of clamp-brackets 21 suitably secured to the framing of the tank by bolts 22, the bars being insulated from the tank by insulating bushings 23 through which the bolts are received and by insulating washers 24, 25, respectively between the head of the bolt and the bracket and between the bracket and the tank.

The articles 27 to be plated form the cathodes of the plating bath arranged to 95 receive the plating from the anodes by means of the electrolytic action in the plating bath.

100 105

Electro-conductive bars 31, 32, extend lengthwise of the plating tank and constitute cathode-bars, exemplified as supported from the sides of the tank by brackets 33 5 mounted on arms 34 secured to the sides of the tank by bolts 35. Each of the brackets is insulated from and secured to its arm by means of a bolt 36 which passes through an insulating sleeve 37 in a hole 38 in the 10 bracket, the insulating sleeve having a flange 39 thereon between the bracket and the head of the bolt 36. The bolt is threaded into the arm 34, an insulating plate 40 being located between the bracket and the arm. 15 The electro-conductive bars 31, 32, are exemplified as stiff bars, which, at their entrance ends, are sloped laterally away from each other, as shown at 41. Flexible electric conductors 42 connect the cathode-bars, 20 which form the negative poles of the plating tank, in multiple with the other pole of the battery or generator. There is an entrance space 45 between the spread ends of the cathode-bars and the entrance end wall 25 46 of the tank and an exit space 47 between the exit ends of the cathode-bars and the exit wall 48 of the tank.

The articles it is desired to plate are exemplified as small pieces of hardware, represented by the cathodes 27, supported in manner to cause the same to descend into the plating bath through the entrance space 45, to pass along the cathode-bars, to have electric connection made therewith in manner to 35 be hereinafter described, and to be raised through the exit space 47 after having received the electrolytic action.

The pieces 27 are exemplified as supported on pins 51 of an article-support 52, the pins 40 extending from cross-bars 53 projecting from a center shank 54. The shank, cross-bars and pins are of electro-conductive material. That portion of the shank and cross-bars subject to the electrolytic action of the 45 electrolyte of the plating bath, is provided with insulation, as shown by the insulating covering 55 about the shank, and the insulating coverings 56 about the cross-bars. These insulating coverings may be coatings of porcelain fused on the article-support.

A plurality of the article-supports is preferably provided, the article-supports being moved lengthwise of and through the plating tank. This may be accomplished in 55 manner to form a continuous operation, as more fully described and claimed in my aforesaid application.

Article-carriers are exemplified at 61, as suspended carriers provided with flanged 60 wheels 62 which move along a pair of tracks 63 suspended by suitable hangers 64 from the ceiling of the room in which the apparatus is located. The tracks are represented as angle-irons supported to face each other. 65 The flanges on the wheels coact with the

inner edges of the angle-irons and act to support the article-support with relation to the cathode-bars, in manner to be hereinafter described.

The article-carriers comprise a main 70 frame 66 which is suspended by a bearing 67 from an axle 68 to which the flanged wheels 62 are secured.

The article-carriers are connected together and propelled along the tracks by a suitable link-chain 71, which is preferably an endless link chain having a path coincident with the preferably endless pair of tracks 63. The main frame 66 may comprise a link 72 of the link chain to which the respective 80 upper and lower parts of the main frame are secured, as by means of bolts 73.

The main frame comprises a depending guide 75 with which a supplemental frame, exemplified as a supporting rod 76, has 85 guided movement, as by being received in a guide-groove 77 of said guide and held therein by means of straps 78. The lower part of said supplemental frame is provided with a fork 79 in which an insulating spool 90 80 is secured, as on a bolt 81 received in bearings 82 in the tines of said fork. The shank 54 of the article-support is provided with a hook 83 arranged to be releasably received over said spool, being received in the annular groove 84 in said spool, so that said shank is insulated from the fork by means of the bottom of said annular groove and the side flanges of said spool. The spool further aids in positioning the article-support with 100 relation to the cathode-bars.

A sheave 86 is fixed on a shaft 87 journaled in a bearing 88 on a bracket 89, extending from the main frame. This shaft has a pinion 90 fast thereon. A flexible 105 connection 91 is secured to the sheave as at 92 and to a lug 93 extending from the supplemental frame 76, so that when the sheave is turned the flexible connection is received in the groove 94 of the sheave for changing 110 the elevation of the article-support.

A lever 96 is pivoted on a stud-shaft 97 located in a bearing 98 in the bracket 89. This lever comprises a gear 99 which meshes with the pinion 90.

Means are provided for swinging the lever and thereby changing the elevation of the article-support. This is shown accomplished by causing coaction between the swinging end of the lever and supplemental tracks 100. 120 Thus the swinging end of the lever is provided with a roller 102 journaled in a fork 104 at the free end of the lever, the fork being preferably located to one side of the main portion of the shank of the lever.

The roller 102 normally rides on the under surface of one of the tracks 63, in which relation the article-support is in lowered position, for instance, located in the plating tank, the lowering being accomplished by 130

permitting the roller to ride along a retreating portion 105 of the supplemental track. When the roller rides along the supplemental track, the article-support is in elevated 5 position, the elevating being accomplished by permitting the roller to ride along the descending portion 106 of the supplemental track. If desired suitable means may be provided for holding the article-support in 10 elevated relation on the article-carrier regardless of the supplemental track, as shown and described in my aforesaid application.

The arrangement provides means whereby a quick raising and a quick descending of 15 the article-support is accomplished for causing entire raising and descending movements within a short range of the progressive travel of the article-supports.

In order to prevent a jarring of the article-support when raised or lowered, and especially to provide for a quick lowering without jarring of the article-support, I provide cushioning means, these cushioning 20 means being exemplified as a spring 107, one end of the spring being received in a hole in the lever and the other end of the spring being hooked into an eye-bolt 108 having adjustable connection by means of a nut 109 with a lug 110 of the main frame 25 for adjusting the spring.

It is desirable to maintain proper relation between the traveling-carrier and the tracks during operation of the lever by preventing a swinging of the carrier about a vertical 30 axis during swinging movement of the lever, the lever being shown at one side of the carrier and to the side of the propelling chain therefor. For accomplishing this I provide the supplemental tracks as grooved tracks 35 having the lengthwise groove 111 formed by the side flanges 112 of the U-bar, which forms the supplemental tracks. A double-flanged wheel 113 is instanced as on the shaft 97, being rotatable on said shaft and 40 held against endwise movement thereon. The flanges of this wheel slope outwardly toward the ends of the wheel, forming a spool-like arrangement. The inner faces of the 45 flanges coat with the outer side edges of the flanges 112 of the supplemental track, for locating the double-flanged wheel centrally 50 with relation to the track.

When in the travel of the article-carrier the roller 102 is received in the groove 111 of 55 the supplemental track and the flanges of the double-flanged wheel are received at the outside of the side flanges of said groove, the travel of the lever is maintained in a path parallel with the tracks 63 and parallel 60 with the cathode-bars, for preventing a swinging of the article-carrier on a vertical axis with relation to the tracks.

Means are provided for insuring proper 65 electric contact between the cathode-support, represented by the article-support, and

the cathode-bars, accomplished in the present instance by placing the cathode-bars at different elevations and in vertical planes extending lengthwise of the path of travel of the article-supports, the cathode-bars being 70 spaced apart by a vertical space 114. The article-support is preferably so suspended that its gravity will cause lateral pressure between the cathode-support and the bars along which it travels. This lateral pressure is instanced as between the shank of the article-support and both the bars, for accomplishing which the suspension of the article-support is had in such manner that the upper bar 31 causes a slight movement laterally of the shank 54 toward the bar 32, the article-support being normally suspended for traveling in a path with its center very slightly to the side of the center of the vertical space 114. The bar 32 acts to urge the 80 shank in the opposite direction.

The weight of the article-support when so contacted employs the bar 31 as a fulcrum for urging the portion of the shank 54 opposite the bar 32 into contact with the bar 90 32, the articulations in the hanging of the article support permitting this slight movement, but insuring such contact with both cathode-bars, the gravity action of the article-support being such as to cause lateral 95 pressure of the shank against both of the bars 31, 32, for insuring intimate electrical contact between said bars and said shank. When the shank 54 approaches the cathode-bars it is readily directed into the space 114 100 100 by the laterally bent ends of said bars, forming a contracting mouth for the entrance end of said space.

When the article-support arrives at the end of the plating tank, it is elevated through 105 the exit space 47 in manner hereinbefore described, the article-carrier continuing its travel.

My improved device insures good electric 110 connection between the cathode-bars and the cathodes while the latter travel lengthwise of the plating tank, so as to receive the full benefit of electrolytic action on the electrolyte and a maximum amount of plating while passing through the tank.

Having thus fully described my invention, what I claim as new and desire to secure by Letters Patent, is:

1. In an electro-plating apparatus, the combination of a plating tank, cathode-terminals extending lengthwise thereof in proximity to each other, a conveyer for the articles to be plated, a cathode-carrier suspended therefrom, said cathode-terminals located at different elevations and said cathode-carrier arranged for laterally pressing said cathode-terminals by gravity.

2. In an electro-plating apparatus, the combination of a plating tank, coacting cathode-terminals extending lengthwise

thereof, a conveyer for the articles to be plated, a cathode-carrier suspended therefrom, said conveyer comprising means for lowering the article-carrying portion of said cathode-carrier into said tank and placing said cathode-carrier in coactive relation with said cathode-terminals, and means for elevating said article-carrying portion of said cathode-carrier out of said tank, said cathode-terminals located at different elevations, and said cathode-carrier arranged for laterally pressing said cathode-terminals by gravity.

3. In an electro-plating apparatus, the combination of a conveyer, an electro-plating tank, coacting cathode-terminals extending lengthwise of said tank spaced from the respective ends of said tank, said cathode-terminals having a vertical space between them, the entrance ends of said cathode-terminals bent laterally away from one another for forming an entering converging mouth for said vertical space, a cathode-carrier comprising a stem and an article attaching portion, said conveyer comprising means for lowering said article attaching portion into one end of said tank and said stem into said converging mouth for guidance into and passage through said vertical space in coactive relation with said cathode-terminals, and said coacting cathode-terminals and said stem arranged for lateral pressure between them.

4. In an electro-plating apparatus, the combination of a plating tank, cathode-terminals therefor in the form of electric cathode-bars extending lengthwise of said plating tank and located at different elevations, a cathode-carrier, and means for suspending said cathode-carrier and moving the same lengthwise of said cathode-bars between said cathode-bars for causing lateral pressure by said cathode-carrier between and against said cathode-bars by the action of gravity upon said cathode-carrier.

5. In an electro-plating apparatus, the combination of a plating tank, cathode-terminals therefor in the form of electric cathode-bars extending lengthwise of said plating tank and located at different elevations, a cathode-carrier and means for suspending said cathode-carrier and moving the same lengthwise of said cathode-bars between said cathode-bars for causing lateral

pressure by said cathode-carrier between 55 and against said cathode-bars by the action of gravity upon said cathode-carrier, said cathode-bars having their entering ends relatively spread for ready entrance of said cathode-carrier.

6. In an electro-plating apparatus, the combination of an electro-plating tank, cathode-terminals in the form of cathode-bars extending lengthwise of said tank, one of said cathode-bars being higher than the other of said cathode-bars, said cathode-bars having a vertical space between them, a cathode-conveyer, and a cathode-carrier suspended from said conveyer, one of said cathode-bars arranged to move said cathode-carrier into contact with the other of said cathode-bars.

7. In an electro-plating apparatus, the combination of an electro-plating tank, cathode-terminals in the form of cathode-bars extending lengthwise of said tank, one of said cathode-bars being higher than the other of said cathode-bars, said cathode-bars having a vertical space between them, there being a vertical space between the ends 80 of said cathode-bars and the ends of said plating tank, a cathode-conveyer and a cathode-carrier suspended from said conveyer, said conveyer comprising means for lowering said cathode-carrier at one of said end spaces and elevating said cathode-carrier at the other of said end spaces, and said higher cathode-bar arranged to move said cathode-carrier into contact with the other of said cathode-bars.

8. In an electro-plating apparatus, the combination of an electro-plating tank, cathode-terminals in the form of cathode-bars extending lengthwise of said tank, said cathode-bars being located at different elevations, said cathode-bars having a space between them, and a cathode-carrier having a part movable lengthwise of and between said bars, and arranged for contact with both said bars.

In testimony whereof I have hereunto signed my name in the presence of two subscribing witnesses.

MICHAEL F. DAVORAN.
